UNITED STATES PATENT OFFICE.

PHILIP S. CLAUS, OF DETROIT, MICHIGAN.

INTERNAL-COMBUSTION ENGINE.

1,076,953.

Specification of Letters Patent. Patented Oct. 28, 1913.

Application filed May 27, 1912. Serial No. 699,869.

To all whom it may concern:

Be it known that I, PHILIP S. CLAUS, a citizen of the United States, residing at Detroit, county of Wayne, State of Michigan, have invented a certain new and useful Improvement in Internal-Combustion Engines, and declare the following to be a full, clear, and exact description of the same, such as will enable others skilled in the art to which it pertains to make and use the same, reference being had to the accompanying drawings, which form a part of this specification.

My invention relates to internal combustion engines and an object of my invention is to provide an improved engine of this type and one in which the control of gases passing through the engine is improved and evenness of wear in the cylinder is secured.

I attain this object in the device illustrated in the accompanying drawings, in which,

Figure 1, is an elevation of one end of a multi-cylinder internal combustion engine embodying my invention. Fig. 2, is a section of all the cylinders taken on the line 2-2 Fig. 1. Fig. 3, is a similar section taken on the line 3-3 Fig. 1. Fig. 4, is a sectional elevation of the engine. Fig. 5, is a sectional elevation of the cylinder and a portion of the crank case showing a modified form of my invention. Fig. 6, is a view similar to Fig. 5 showing the second modified form of my invention. Fig. 7, is a detail plan view of a portion of the top of one of the cylinders.

A, is the crank case, and B, is a cylinder having a water jacket.

C, is a distance piece uniting the cylinder B with the crank case A. The distance piece C contains a casing for the gearing hereinafter described.

D, is a cylinder fitting in the cylinder B and the distance piece C, and adapted to reciprocate and rotate therein.

E, is a piston adapted to reciprocate in the cylinder D.

F, is a connecting rod, the upper end of which is connected to the piston E by a universal joint, or, as shown in Fig. 4, by a ball and socket joint, the connection being such as to permit the oscillation of the connecting rod and the rotation of the piston. The lower end of the connecting rod F is connected to the main shaft G of the engine by the usual crank.

H, is a counter shaft resting in bearings in

the crank case A parallel to the main shaft of the engine. The shaft H is connected to the main shaft by a sprocket gearing, in the present instance, the chain of which is indicated by the reference letter T.

I, is a connecting rod, its upper end connected to the lower end of the cylinder D, by being pivoted to the ring Z, which ring is included between two annular lugs z z except in the form shown in Fig. 5 where the gear S¹ takes the place of one of said annular lugs. The lower end of the connecting rod I is connected by an eccentric mechanism to the shaft H.

J, is an aperture through the upper part of the vertical walls of the cylinder D. The aperture J may register with the intake port M to permit the in-draft of explosive mixture, or with the exhaust port N to permit the exit of the products of combustion.

K, is an aperture similar to the aperture J through the vertical wall of the cylinder D just above the position at which the upper end of the piston comes at its lower dead center. The aperture K is adapted to register with an auxiliary intake port L or with an auxiliary exhaust port O. The exhaust ports N and O communicate with the same pipe from which leads an exhaust pipe P.

Q, is a helical gear wheel upon a shaft R which is connected by a chain t with the main shaft of the engine.

S, is an annulus having teeth with which the teeth of the gear wheel W engage.

The operation of the above described device is as follows: When the engine is running, the cylinder D is continually reciprocated by the connecting rod I geared to the main shaft of the engine. The cylinder is at the same time rotated by the gear Q, which is also geared to the engine shaft. Thus the cylinder D has two motions, one of reciprocation and one of rotation. The apertures J K are made slanting, as shown, and the ports M and L are made of corresponding form so that the sides of said apertures and ports are at right angles to the motion of the cylinder due to its reciprocation and revolution, thus the ports are opened and closed rapidly. There may of course be a number of apertures J and K to correspond to the cycle of the engine and speed of rotation of the cylinder D. The rotation of the cylinder D and its reciprocation together with the action of the engine will gradually

change the angular position relative to the cylinder D so that the wear shall not be all in one spot. The universal joint at f permits of the rotation of the piston E with the cylinder D so that less friction is developed than would be incident to a connection which would require that the entire rotary motion of the cylinder D should be a motion relative to the piston E. W X are apertures formed through the top of the cylinder D toward its periphery. These apertures are so located that they come opposite the apertures U V Y in the top of the cylinder B as the cylinder D rotates. Thus the sparking plug which passes through the aperture U in the cylinder B may extend through the aperture W into the cylinder D to ignite the charge therein. An oil supply apparatus may be placed in the aperture V and the discharge from this apparatus may pass through the aperture X. A priming cup may be placed at Y above the path of the apertures W and K so that the hydrocarbon may be allowed to pass therefrom into the cylinder D to start the engine.

In the modification shown in Fig. 5, instead of a helical gear S, I have shown a gear S¹ with straight teeth and the motion is communicated from the crank shaft G by the bevel gear wheel b the shaft c and spur gear wheel d.

In the form of device shown in Fig. 6, I have provided the cylinder D with a slot m into which extends a stationary plug n. The reciprocation of the cylinder D will now give the said cylinder a limited rotary, or an oscillating motion, and a longitudinal or reciprocating motion, this being a different way of accomplishing the same result, as shown in the first form of device. Thus I wish it to be understood that when I refer to a rotary motion I include an oscillatory motion as one form of rotary motion.

In the form of device shown in Figs. 5 and 6 the upper end of the inner cylinder is closed and an aperture W^a is formed in its side wall, which aperture is closed by the wall of the outer cylinder, but, when the explosion takes place is directly opposite the sparking plug extending through an aperture in the side of the outer cylinder in the usual way. In this form of device the explosion chamber is entirely within the inner cylinder and the motion of the inner cylinder is so adjusted as to make its head approach the upper end of the piston at the

end of the exhaust stroke so as to completely expel the residual gases.

What I claim is:—

1. In an internal combustion engine, a cylinder, a second cylinder having one end closed adapted to reciprocate in the first named cylinder, ports through the wall of the first named cylinder, an aperture through the wall of the second cylinder 65 adapted to register with said ports, a piston adapted to reciprocate in the second cylinder, and means for giving the second cylinder a movement of rotation and reciprocation whereby the motion of the second cylinder 70 controls the passage of gas therethrough.

2. In an internal combustion engine, a cylinder, a second cylinder having one end closed adapted to reciprocate in the first 75 named cylinder, ports through the wall of the first named cylinder, an aperture through the wall of the second cylinder adapted to register with said ports, a piston adapted to reciprocate in the second cylinder, and 80 means for giving the second cylinder a movement of rotation and reciprocation whereby the motion of the second cylinder controls the passage of gas therethrough, the reciprocating motion of said second cylinder 85 being timed with reference to the movement of said piston so that the residual gases shall be completely expelled at the end of the exhaust stroke.

3. In an internal combustion engine, a cylinder, a second cylinder having one end closed adapted to reciprocate in the first named cylinder, ports through the wall of the first named cylinder, an aperture through the wall of the second cylinder 90 adapted to register with said ports, a piston adapted to reciprocate in the second cylinder, and means for giving the second cylinder a movement of reciprocation whereby the motion of the second cylinder controls the passage of gas therethrough, the reciprocating motion of said second cylinder being timed with reference to the movement of said piston so that the residual gases shall be completely expelled at the end of the 100 exhaust stroke.

In testimony whereof, I sign this specification in the presence of two witnesses.

PHILIP S. CLAUS.
